UNITED STATES PATENT OFFICE.

FRED W. SCHWEITZER, OF MONITOR TOWNSHIP, BAY COUNTY, MICHIGAN.

GRADER.

1,413,687.

Specification of Letters Patent. Patented Apr. 25, 1922.

Application filed September 7, 1920. Serial No. 408,526.

To all whom it may concern:

Be it known that I, FRED W. SCHWEITZER, a citizen of the United States of America, residing at Monitor Township, in the county 5 of Bay and State of Michigan, have invented certain new and useful Improvements in Graders, of which the following is a specification.

This invention relates to graders and the 10 like.

One object of the invention is to design a grader which will require a minimum amount of power to operate.

Another object is to provide a grader 15 which can be turned from operative position and which can be readily drawn over the soil and roadways.

A still further object is to construct a machine which can be used as a ditcher for 20 farm use and which will also be equally efficient for grading the usual roadways.

With the above and other objects in view, the present invention consists in the combination and arrangement of the different 25 parts, hereinafter more fully described, illustrated in the accompanying drawings and more particularly pointed out in the appended claims, it being understood that changes may be made in the form, size, proportion 30 and minor details without departing from the spirit or sacrificing any of the advantages of the invention.

In the drawings:

Figure 1 is a side view of my improved 35 grader.

Figure 2 is a top plan view thereof.

Figure 3 is a section taken on the line 3—3 of Fig. 1, and

Figure 4 is a rear view of the grader illustrating it inoperative position.

Referring now particularly to the drawing in which the landside of the grader is indicated by the numeral 1, and to which is rigidly secured the moldboard 2 by means of 45 the brace members 3 and 4, the said brace members being secured to the landside and mold-board by means of bolts or countersunk rivets, so that the outer surface of the mold-board may present a smooth appearance. 50 This mold-board is curved to roll the soil and is secured to the forward end of the landside, a spacer member 5 being positioned as shown in Figures 2 and 3.

As designed the grader is to be drawn by 55 horses, the draft bar 6 being secured to the mold-board and extends transversely

through the landside and is provided with openings 7 therein for attachment of the clevis 8, a brace bar 9 extending rearwardly and being secured to an eyebolt 10 set in the 60 landside.

A platform 11 is provided as shown on which the driver rides, and this platform is so positioned that the weight of the driver thereon will nicely balance the draft of the 65 grader. Hand rings 12 are secured to the landside and the brace 4 respectively for the convenience of the driver in pulling the grader back when occasion requires.

It will be obvious that when the grader 70 is operating on a ditch or roadway that the tendency of the mold-board will be to slide the landside, and I therefore provide the plate member 13 which I securely fasten to the landside as shown, and which extends 75 into the soil and acts as a rudder for the grader, the plate extending below the ground line a distance at least equal to the depth of cut of the mold-board.

I wish to direct particular attention to 80 the shape of the landside which is cut out as shown at 14, the depth thereof being less at the rear than at the front, this is to provide clearance for large stones, sticks, or other foreign matter which would otherwise raise the grader and rudder and allow the grader to slide, by forming this landside as shown, stones and other obstacles will merely raise the forward end of the grader, and the rudder being relatively thin and 85 sharp will force them to either side thereof.

In moving graders of this type from one location to another the grader generally digs in to a certain extent, due to its weight, this is unsatisfactory and I have overcome this 95 by designing it to be turned on its side and securing the wheel members 15, by means of brackets or the like to the forward end thereof, these wheels extend slightly below the bottom of the landside when it is in the 100 position shown in Figure 4, and carry the forward end of the grader free from the roadway, the rear end dragging and it will be noted that whatever wear there is will be on the steel rudder plate 13. For turning 105 the grader to the position shown in Fig. 4 a detachable handle 16 is provided and is seated on the keepers 17 secured to the inner side of the mold-board, this handle can be of any convenient length to enable the 110 operator to easily turn the grader to operative or inoperative position.

From the foregoing description it will be obvious that I have perfected a simple and inexpensive grader, very efficient in operation, which will not slide, and which can 5 be readily converted and transported from one location to another.

What I claim is:—

1. In a grading apparatus comprising an elongated landside having a mold-board rigidly secured thereto, steering means secured to the rear end of said landside, and wheels secured to the forward end of the mold-board for raising and supporting the forward end of the grader above the ground 15 level when the grader is turned to inoperative position.
2. In a grading apparatus comprising a landside having a mold-board secured thereto, the forward end of said landside being of greater depth than the rear end for clearing obstacles and the like, a plate rigidly 20

secured to the rear end of the landside and extending downwardly therefrom, wheels journaled to the front end of the landside and adapted to support the forward end of 25 the grader above the ground when the grader is turned to inoperative position.

3. In a grading apparatus comprising a landside having a mold-board rigidly secured thereto and spaced therefrom, the forward end of said landside being of greater depth than the rear end for clearing obstacles and the like, a rudder plate secured to the rear end of the landside, a detachable handle for turning the grader to inoperative 30 position, and wheels journaled to the forward end of the mold-board and adapted to support the forward end of the grader clear of the ground when the grader is turned 35 to inoperative position.

In testimony whereof I affix my signature.

FRED W. SCHWEITZER.
